LINE GRIPPING DEVICE

James D. Monie, Scranton, Pa.

Application February 14, 1946, Serial No. 647,559

2 Claims. (Cl. 24—133)

1

This invention relates to improvements in line-gripping devices of the type shown in the U. S. patent to W. L. Kelly, No. 1,571,336, dated February 2, 1926.

An important object of the present invention is to provide an improved locking device to keep the gripping lever or dog in gripping position irrespective of the varying tension on the line due to the swaying action of the wind or tide upon the extended line.

A further object of the invention is to so construct the device as to adapt it for use in connection with anchor or mooring ropes for boats, the gripping means being carried by a swivelled post so as to overcome any tendency of the line to slip out of the groove of the gripping lever by permitting the clamping means to turn in the direction of the tension on the line.

A further object of the invention is to provide means whereby the form of the device adapted for holding anchor and mooring lines may be readily mounted on a boat for use or removed therefrom for safekeeping when not in use.

Another object of the invention is to adapt the device for use as a wire-gripping device for wire stretchers and to enable the wire or line to be readily engaged with the gripping lever without threading it through the opening of the arm in which the gripping lever or dog is pivoted.

The exact nature of the present invention will become apparent from the following description when considered in connection with the accompanying drawings, in which:

Figure 1 is a vertical, longitudinal, sectional view of a gripping device constructed in accordance with the present invention and adapted for use as a clothesline holder.

Figure 2 is a perspective view of the locking element for the line-gripping lever.

Figure 3 is a view partly in side elevation and partly broken away and in section, showing a modification of the device illustrated in Figure 1.

Figure 4 is a view partly in side elevation and partly in section of a form of the invention adapted for use as a holder for anchor and mooring lines.

Figure 5 is an enlarged fragmentary, transverse section taken on line 5—5 of Figure 4.

Figure 6 is a top plan view of the keeper base forming part of the device shown in Figure 4.

Figure 7 is a transverse section taken on the line 7—7 of Figure 6.

Figure 8 is a side elevational view of an embodiment of the invention adapted for use as a

2

wire-gripping device for wire stretchers, or the like.

Figure 9 is a top plan view of the part of the device shown in Figure 8 in which the gripping lever is pivoted.

Figure 10 is side elevation showing a modification of the embodiment of Figures 8 and 9, and illustrating it in use for connecting the ends of a pulley clothesline.

Referring in detail to the drawings, the present gripping device includes an attaching member 5 having a laterally extending arm 6 provided, at its outer or free end, with a vertical opening 7. At the outer end of the opening 7, the arm 6 is formed to provide a transverse, cylindrical pivot bar 8.

The device further includes a gripping lever or dog 9 which is in the form of a compound curve and is disposed to extend through the opening 7 so as to present a rearwardly directed, lower end 10 underlying the portion of arm 6 directly at the rear of the opening 7 and where said arm is shaped to form a gripping face 11. The rearwardly directed end 10 is formed with teeth 12 to grip the portion of the rope or line disposed between the end 10 and the face 11. The dog or lever 9 is provided in its rear face with a longitudinal groove 13 that extends from the teeth 12 through the forwardly directed upper end 14 of the lever. In order to prevent the lever 9 from passing downwardly through the opening 7, it is provided intermediate its ends and on opposite sides with shoulders 15 adapted to rest on the arm 6 at opposite sides of the opening 7. The terminal of the end 10 is also provided with a groove 16 to hold the line in place, if desired. In the form of the invention shown in Figure 1, the attaching member 5 is in the form of a vertical base plate provided with end slots 17 for receiving screws, or the like, which secure the device to a support.

Thus far described, the device of Figure 1 is similar to that disclosed in the Kelly patent mentioned above, the lever 9 being formed at the front and intermediate its ends with a transverse groove 18 which conforms to and receives the pivot bar 8 so that the lever 9 is pivotally and removably mounted in the opening 7 of arm 6.

The present invention contemplates provision of the lever 9 with a locking element 19 to keep the lever in gripping position and thereby maintain its grip upon the rope or line irrespective of the varying tension of the rope or line in the direction of the arrow *a* due to the swaying

action of the wind or tide upon the extended rope or line. As shown, this locking element is preferably in the form of an elongated wire bail having transversely aligned, inturned ends 20 pivotally engaged in a transverse opening provided in the upper end portion 14 of the lever 9, as at 21, said bail being of a length to engage the attaching member 5 above and adjacent the arm 6 when said element 19 is disposed at a rearward inclination and the end 10 of lever 9 has a secure gripping engagement with the rope or line, as shown in Figure 1. While the locking element 19 will remain in locking position by frictional engagement of its end with the attaching member 5, the latter is preferably provided with a shallow, transverse groove or notch 22 into which the end of the element 19 is adapted to snap when said element is in locking position, the snapping action being had due to the resiliency of the element 19.

The embodiment of the invention shown in Figure 3 is identical to that shown in Figure 1, except that the upper end 14 of the gripping lever 9 is bifurcated as at 23, and a grooved pulley 24 is journaled between the furcations of this end upon a transverse pin 25. By using the pulley 24, the ease of movement of the rope or line is promoted when placing it under tension prior to final gripping engagement of the end 10 with the rope or line.

Referring to Figures 4 to 7, inclusive, which show an embodiment particularly adapted for use in connection with anchor and mooring lines for boats, the attaching member 5a is horizontally disposed and has the lower end of a vertical post 26 swivelled therein so as to overcome any tendency of the rope to slip or move out of the groove of the gripping lever by permitting the gripping means to turn in the direction of the tension on the rope or line. In this embodiment, the arm 6 extends laterally from the upper end of the post 26, and the swivel connection of the post 26 with the attaching member 5a may be provided as shown in Figure 5. For this purpose, the attaching member 5 may be provided with a central, hollow boss 27 which rotatably receives a circular enlarged head 28 on the lower end of the post 26, said head being retained in the boss by means of a centrally apertured cap 29 that is threaded onto the boss. The cap 29 has a central opening through which the post 26 rotatably extends, the top wall of the cap surrounding the post 26 overlying the head 28. As an additional safeguard against slipping of the rope, the post 26 may be provided below the arm 6 with an opening 30 through which the end of the rope or line may be passed for being knotted at 31 at the back of the post 26. It is desirable to provide means whereby the device of Figure 4 may be readily mounted upon the coaming or other part of a boat for use and removed for safekeeping when not in use. For this purpose, I provide a keeper base 32 for removable, slidable reception of the attaching member 5a. The keeper base 32 is in the form of a flat plate having openings 33 for reception of screws, or the like, so that the keeper base may be secured upon the coaming or other part of the boat, said plate being provided along both sides and at one end with inwardly projecting, overhanging flanges 34 forming ways to receive the side portions and an end portion of the attaching member 5a to retain the device in place. The keeper plate is disposed so that its end flange 34 forms a stop for engagement with the end of the attaching member 5a to

prevent movement of the device by and in the direction of the tension on the rope or line. Obviously, when the rope or line is released, sufficient slack may be had therein to permit the attaching member 5a to be slid longitudinally out of the keeper base 32, whereupon the device is detached and can be put away for safe keeping when not in use.

The form of the invention shown in Figures 8 and 9 is particularly adapted for use as a tightening device for pulley clotheslines or as a gripping device for wire stretchers. It is similar to the embodiment of Figure 1 except that the attaching member 5b is in the form of an upward extension of the inner end of arm 6 and is provided at its upper end with a horizontal, rearwardly projecting integral eye member 35 to facilitate connection of the attaching member to one end of the clothesline, or to part of a wire stretcher by means of a chain 36, or the like. In addition, the end of the arm 6 which is provided with the opening 7 may be provided at one side with a substantially vertical slot 37 that is open at its ends to permit insertion of the other end of the wire or line 38 laterally through said slot and into the opening 7 for engagement with the gripping lever 9. This obviates the necessity of threading the wire or line through the opening 7 such as is necessary when the slot 37 is not provided.

In Figure 10, the device is similar to that of Figures 8 and 9, except that the slot 37 is not provided. As shown, it is used to connect the ends of a clothesline 39 that passes around spaced pulleys 40 and 41 attached to supports 42 and 43. One end of the line 39 is knotted at 44 and passed through the eye member 35 to anchor that end to the arm 6. The other end of the line is passed over lever or dog 9 and through the opening which receives said lever or dog, so as to be gripped at 11 and 12, as described relative to the other forms.

In operation, the rope or line is extended through the opening 7 behind the lever 9, and the rope or line is placed under tension by pulling it in a direction opposite to that indicated by the arrow a. This tension swings the lever 9 on the pivot bar 8 so that the rope or line is clamped between the end 10 of lever 9 and the face 11 of arm 6. By swinging the lever 9 so that its lower end moves forwardly, the gripping action on the rope or line is released, but this can only be effected after the locking element 19 is snapped out of the notch 22 and swung upwardly to released position. When the element 19 is swung downwardly to locking position, as shown, the lever is positively held in position to maintain its grip upon the rope or line.

From the foregoing description, it is believed that the construction, operation and advantages of the present invention will be readily understood and appreciated by those skilled in the art. Obviously, the invention may find embodiments in other forms and is susceptible to minor changes in details of construction such as fall within the scope of the invention as claimed.

What I claim is:

1. A line-gripping device comprising, in combination with an attaching member having an arm, and a line-guiding and engaging lever carried by the arm and movable by tension of the line against one end thereof to bring the other end of the same into engagement with the line, means to releasably latch said lever in line-engaging position embodying an elongated bail pivoted at

one end to said one end of said lever and engageable at its other end with the side of said attaching member which is nearer the lever.

2. A line-gripping device comprising, in combination with an attaching member having an arm, and a line-guiding and engaging lever carried by the arm and movable by tension of the line against one end thereof to bring the other end of the same into engagement with the line, means to releasably latch said lever in line-engaging position embodying an elongated thrust bail pivoted at one end to said one end of said lever and engageable at its other end with the side of said attaching member which is nearer the lever, said attaching member having a notch adjacent the arm, and said bail being resilient and adapted to have its other end snapped into said notch.
